UNITED STATES PATENT OFFICE

2,399,307

ANTISWEEP ANCHORAGE FOR MINES OF
THE MARINE TYPE

Charles S. Allen, Jr., Greenville, S. C.

Application November 17, 1942, Serial No. 465,915

1 Claim. (Cl. 102—15)

This invention has reference generally to improvements in that class of inventions known as ammunition and explosive devices, and more particularly relates to an anti-sweep anchorage for mines of the marine type.

It is the primary aim and object of the present invention to provide a device of the above character interposed in the anchoring cable at a suitable point between the anchor and the mine to act as a means for releasing a sweeping cable after the sweeping cable has engaged the anchoring cable in order to prevent the mine from being disturbed.

More particularly, the invention embraces the provision of a device of the above character embodying generally a spoked cable releasing wheel having a circular track for operatively receiving roller members, the wheel being adapted for connection with one section of the cable while the roller members are adapted for connection with the other section of the cable, the diameter of the roller members being less than the length of the spokes of the wheel so as to insure the passage of the sweeping cable thereby after it has been engaged with the anchoring cable.

Other objects, as well as the nature characteristic features and scope of the invention will be more readily apparent from the following description taken in connection with the accompanying drawing and pointed out in the claim forming a part of this specification.

The invention is clearly illustrated in the accompanying drawing, in which:

Figure 1 is a perspective detail showing one form of the device in operation, the dotted lines showing positions assumed by the sweeping cable as it engages the anchoring cable of the mine and the cable releasing means, the full lines showing the sweeping cable after it has been released from the anchoring cable.

Figure 2 is a side elevational view of the improved anti-sweeping or cable releasing means.

Figure 3 is a vertical sectional view taken in a plane at right angles to Figure 2, while

Figure 4 is a vertical sectional view of a modification.

Similar characters of reference are employed in all of the above described views to indicate corresponding parts.

Referring now, more particularly, to the accompanying drawing, there is illustrated in Figure 1 a mine 1 of the marine type which is anchored to the bottom of the body of water by means of an anchor 2 and a cable 3 which is interposed between the anchor and the mine and

serves to hold the mine normally and generally in a submerged position beneath the water. Interposed in the cable is the improved anti-sweeping or cable releasing means generally designated 4, the purpose of which is to allow the passage of a sweeping cable 5 which is dragged in a looped manner through the water by means of boats 6, from one side of the cable 3 to the other without actually disturbing the position of the mine 1.

10 The improved anti-sweeping or cable releasing means 4 may be said to consist of a sectional cable releasing wheel 7, the spokes 8 of the sections of which are maintained in registration by suitable fastening devices 9 which pass through 15 the hub portions of the wheel sections and through bossed portions or spacing members 10. The wheel is provided with a circular track and as shown in Figs. 2 and 3 the sections are shaped to form a cage and includes an internal circular 20 raceway near its periphery and this raceway is preferably provided by bending the outer ends of the spokes 8 inwardly toward each other as at 11 to form a divided circular track, while operating on this track and within the cage is a rolling 25 means, in this instance in the form of a pair of rollers 12 rotatably mounted on a small axle 13 carried by the upper end of a hanger member 14, the opposite end of which latter is connected to 30 that portion of the cable 3 leading to the anchor 2, the hanger member passing between the spaces between the opposed inturned portions of 35 opposed spokes which form the divided track. A hanger 15 in the form of a fork is connected with that part of the cable 2 leading to the mine 35 while the arms of the fork are preferably arranged on the outside of the wheel and receive an axle 16 on which the sectional wheel 7 is mounted, as clearly shown in the drawing. The ends of the axle 16 have mounted thereon suitable retaining elements such as nuts 17 which 40 are removably engaged therewith for assembly purposes. Obviously the device could be readily inverted; that is, the hanger 14 may be connected to the upper section of the mine cable while the 45 hanger 15 may be connected to the lower section, the main point being the fact that the slots between the spokes or teeth of the wheel are of greater depth than the diameter of the rollers 12, so that when the sweeping cable 5 is engaged 50 in one of the slots between adjacent spokes it will pass by the rollers and thereby be moved from one side of the cable 3 to the other without disturbing the mine.

In Figure 4 there is shown a slightly modified 55 form of the arrangement in which the spoked

wheel 7¹ is formed in a single piece and includes a thickened hub which is axially and rotatably mounted on an axle 16¹, the ends of which are journaled in the arms of the fork-like hanger 15¹. The spokes 8¹ are formed on their outer ends with lateral projections 11¹ which extend in opposite directions beyond the side faces of the wheel which are arranged in circular series of periphery to form tracks on opposite sides of the spokes. Operating on these tracks is a rolling means in the form of rollers 12¹, the latter being in turn mounted for axial rotation on stub axles 13¹ which are journaled in the upper ends of the arms of a U-shaped fork-like hanger 14¹. The hangers 14¹ and 15¹, of course, are adapted to be connected with the cable sections leading to the anchor and the mine, as in the form shown in Figures 2 and 3.

In operation, assuming that the parts have been assembled as described with particular reference to Figure 1, it will be noted that when the sweeping cable 5 first engages the anchoring cable 3 it will slide up the latter to the release device 4 where it will engage one of the slots between the spokes 8 and cause a rotation of the wheel 7 and will pass over the rollers 12 and thence to the other side of the cable 3, as shown

in full lines, allowing the mine to substantially remain in its original set position.

It is believed in view of the foregoing description that a further detailed description of the operation of the invention is entirely unnecessary. Likewise, it is believed that the advantages of the invention will be readily apparent.

Having thus fully described the invention, what is claimed as new and desired to be secured by Letters Patent is:

An anti-sweeping anchorage for mines and the like including a mine anchoring cable divided into sections and sweeping cable releasing means interposed between the anchoring cable sections including U-shaped anchoring members connected to the adjacent ends of the divided cable sections, a spoked wheel rotatably mounted between the arms of one of the U-shaped anchoring members, lateral projections extending in opposite directions at the outer ends of each of the spokes to provide internal peripheral tracks and axially aligned rollers rotatably mounted on the inner surfaces of the arms of the other U-shaped anchor member and for rolling contact with the tracks and having a diameter less than the length of the spokes of the wheel.

CHARLES S. ALLEN, JR.
